CAR-SEAT.

No. 830,410.

Specification of Letters Patent.

Patented Sept. 4, 1906.

Application filed May 19, 1905. Serial No. 261,180.

To all whom it may concern:

Be it known that we, EDWARD G. BUDD and CHARLES A. CONDÉ, citizens of the United States, residing at Philadelphia, in the county of Philadelphia and State of Pennsylvania, have invented a certain new and useful Improvement in Car-Seats, of which the following is a specification.

The object of the present invention is to provide a car-seat structure of the "walk-over" type possessing great strength and durability, the moving parts thereof, including the mechanism for supporting and guiding the back and for shifting the seat-cushion, being characterized by positive mechanical coaction.

A further object of the invention is to provide means whereby the back reversing and guiding mechanism may be relieved of a large portion of the weight of the back, such weight being carried in the main by suitable supports forming part of the stationary seat structure.

In carrying out the invention we employ a walk-over seat-back mounted (detachably or otherwise) upon side arms lying in the plane of such back and the lower ends whereof extend downward for coaction with stops carried by the seat-frame. Coacting with these back-supporting arms at each side are two levers pivoted centrally of the seat-frame and at their other ends pivotally connected with one of such back-arms, the latter pivotal points being in the longitudinal center of such back-arm. At the points of pivotal connection of said levers and the seat-frame we employ positively-coacting mechanism between such levers, whereby the movement of reversal of the seat-back is made smooth and continuous, lost motion is avoided, and ease of operation in changing the seat from one facing direction to the other is effected. This mechanism will be pointed out in detail hereinafter.

The invention is illustrated in the accompanying drawings, in which—

Figure 1 is a side elevation of a car-seat embodying our invention, showing, however, one of the end frame-plates removed to expose the back supporting and reversing mechanism. Fig. 2 is a central cross-section. Fig. 3 is a plan view on the line 3 3, Fig. 1, illustrating the back supporting and guiding

mechanism apart from the other structural features of the seat. Fig. 4 is an elevation, partly in section. Fig. 5 is an enlarged detail view illustrating the coacting mechanism between the ends of the levers pivoted to the frame and to the back-supporting arms. Fig. 6 is an end elevation illustrating a modification and omitting superfluous parts, such as seat and back cushions, supporting-frame, &c. Fig. 7 is a section on the line 7 7, Fig. 6; and Fig. 8 is an enlarged perspective view illustrating the coacting mechanism intermediate of the ends of the levers shown in Fig. 6.

Referring first to Figs. 1 to 5, inclusive, it will be seen that the structure here illustrated includes a supporting frame or pedestal A and sills or rails *a* extending between and connecting the same, said sills or rails supporting rockers B, carrying seat-cushion C. It is contemplated that the seat supporting and reversing mechanism at each end of the seat shall be the same in construction, although, as is well understood in this art, this may not be observed in practice—as, for instance, the mechanism at the aisle end of the structure may be that hereinafter described, that at the wall end of the car being of such a character as not to interfere with the operation or sacrifice the advantages of the mechanism at such aisle end. We shall therefore describe in detail only the mechanism at one end of the seat structure. Supported in any suitable manner upon the seat support or pedestal A is an inner end plate D, the side edges *d* whereof are flanged outwardly at an angle to the body portion thereof, as clearly shown in Fig. 3. E E designate stops, here shown as comprising straps or bearing-pieces of right-angular cross-section, the lower webs *e* whereof are riveted or otherwise secured to the plate D and the upper webs *e'* whereof form shelves to receive the back-supporting arm hereinafter described. Riveted or otherwise secured upon the webs *e'* are buffers, which may be of wood or of several thicknesses of leather, as desired. These buffers receive the impact of one of the back-supporting arms when the latter assumes operative position in either of the facing directions of the seat. F designates the walk-over seat-back, here shown as provided with a socket *f*, with which engages the back-supporting arm *f'*, having the foot *f''* coacting with one or the other of

the stops above described. G H designate, respectively, the upper and lower back-guiding levers, the former of which is pivoted at one end g to the back-arm f' and at its other end upon a stud g' , extending through and journaled in the inner end plate D. The back-guiding lever H is pivoted at one end h to the back-arm f' and at its other end is supported upon a collar h' , keyed or otherwise secured to said lever H and extending through the inner end plate D, where it is secured, by key or other means, to the tie-rod I, extending between and connecting the movement at one end of the seat with that at the other in order to synchronize the operation of such movements. As clearly shown in Fig. 3, the lower enlarged ends of the levers G H lie in the same vertical plane. Each of said levers, however, is provided with a shoulder (marked g^2 g^3 , respectively,) whereby such levers intermediate of the shoulders and the pivotal points g h are separated from each other by a substantial distance, enabling them to clear each other in their movement from one position to the other and in addition to permit the pivotal point of the lever G to be on one side of the back-arm f' and the pivotal point h upon the other, as illustrated in Fig. 1. L designates a check-block 25 secured by screws l to a stud l' , extending through the inner end plate D and provided outside the same with enlarged head l'' , said check-block being thus supported on said inner end plate in such manner as to permit the same to oscillate under the influence of the levers G H, as presently explained. Said check-block is provided with oppositely-arranged semicircular cut-away portions l^1 l^2 , and on either side of the cut-away portion l^1 with substantially straight portions l^3 l^4 , and on either side of the cut-away portion l^2 with substantially straight portions l^5 l^6 . The lever G is provided with wings g^4 g^5 on either side of its pivotal point g' , and carried by each of these wings and between such wings and the inner end plate D is a stud g^6 g^7 . These studs may be of any desired configuration, but we prefer to make them in the form of round pins cut away at their side edges in parallel planes, as illustrated in Fig. 5. The lever H is also provided with wings h^2 h^3 , and these wings also are provided with studs h^4 h^5 , which may, if desired, be similar to the studs g^6 g^7 . The studs g^6 g^7 and the studs h^4 h^5 coact with the oscillating check-block L in such manner as that by means of such check-block the back-guiding levers G H shall at all times be mechanically interrelated, whereby the movement of the back from one to the other facing direction of the seat is made uniform and continuous and lost motion avoided. This positive mechanical interrelation will readily be understood from Fig. 5 of the drawings, illustrating the seat parts in the position shown in Fig. 2.

Here the stud g^6 of the lever G and the stud h^4 of the lever H are in coaction with the semicircular cut-away portions l^3 l^4 , respectively, of the check-block L. In the movement of the back from the Fig. 2 position to the Fig. 1 position the stud g^6 rides up the curved side of the cut-away portion l^3 until it escapes therefrom. At the moment of such escape the stud g^7 comes into coaction with the substantially straight portion l^5 on the other side of the cut-away portion l^2 of the check-block. During the movement as thus far traced the action of the stud h^4 of the lever H is substantially the same as that of the stud g^6 of the lever G, and the action of the stud h^5 of the lever H is substantially the same as that of the stud g^7 of the lever G. If now the movement be continued, so that the back-arm f' and the levers G and H shall lie in truly vertical and parallel planes, the studs g^6 g^7 of the lever G will both coact with the substantially straight portions l^5 l^6 at the upper edge of the check-block L, and the studs h^4 h^5 will coact with the similar portions l^3 l^4 at the lower edge of the check-block L, and the latter will be turned on its pivot. The movement being continued so as to bring the back to the Fig. 1 position, the stud g^6 rides along the substantially straight portion l^5 to the right, and the stud g^7 escapes from the substantially straight portion l^5 at the other side of the check-block and enters the cut-away portion l^2 , remaining in contact with the edge of such cut-away portion. This action is true also of the studs h^4 h^5 of the lever H. It will thus be seen that the lower ends of the levers G H are, as above stated, at all times in positive mechanical coaction, with the advantageous result above referred to.

The plate D has been herein referred to as the "inner" end plate, for the reason that we prefer to employ two parallel end plates at each end of the seat and in the present disclosure have illustrated, therefore, the outer end plate D', provided, like the inner plate D, with angularly-flanged edges d' , coacting with the flanged edges d of the inner plate D and secured thereto, preferably by means of bolts or screws d^2 . Also we prefer to employ tubular struts d^3 , secured upon the inner face of the outer end plate D' and extending between said plate D' and the inner end plate D. Extending through said struts d^3 and through the plates D D' are bolts d^4 , which, together with the edge bolts d^2 , bind the two end sections (comprising the plates D D') firmly and rigidly together, said bolts preventing the movement of such plates away from each other and the struts d^3 preventing movement thereof toward each other. If, as in the construction now being described, a seat-cushion of the shifting type be employed, the movement of this, coextensively with that of the back, may be accom-

plished by means of a lever M, keyed or otherwise secured upon the tie-rod I and having at its end a stud m, coacting with a slot m', formed in the rocker B or an appurtenance thereof. In this manner the movement of the back transmits corresponding movement to the seat-cushion by way of the lever H, tie-rod I, lever M, and rocker B.

In Figs. 6, 7, and 8 we have illustrated a modification of the construction above described, this involving the use of mechanism serving the same purpose of positively correlating the levers (G', H' in said figures) not only in their ultimate positions, but also during their movement from one of such positions to the other. The intermediate check-block here takes circular form, as shown at N, and is provided with the slots n, n' and the raised portion n', the edges of the latter being cut away at n², n³, n⁴, and n⁵ to form what we term "dwells" for coaction with the round ends of the levers G', H'. Said check-block is pivotally mounted, as shown at n⁶, upon the inner end plate, the main (circular) portion thereof underlying the ends of said levers G', H' and the dwells n², n³, n⁴, n⁵ lying in the same plane as said ends of said levers. The lever G' is provided with a stud G² beyond the point at which said lever is pivotally secured to the end plate and lying between said lever and said end plate. The lever H' is provided with a similar stud H² intermediate of the two pivotal points of said lever and between said lever and said end plates. The stud G² coacts with the slot n and the stud H² with the slot n'. As clearly shown in Fig. 6, a portion of the rounded end of each of the levers G', H' is in coaction with one of the dwells upon the raised portion n'. As the back is moved to the left this coaction continues until the studs G², H² enter their coacting slots in the check-block N, when said check-block is rotated upon its pivot n⁶. As the movement is continued and the studs G², H² ride out of their coacting slots the curved edge of each of the levers on the opposite side comes into coaction with one of the dwells upon the raised portion n', thus maintaining the lower ends of said levers G', H' in positive mechanical coaction at all times, including, as above stated, not only the ultimate positions of the back, but also during the movement of said back intermediate of such positions.

Having now described our invention, what we claim as new therein, and desire to secure by Letters Patent, is as follows:

1. In a reversible car-seat, the combination of a frame, a seat and a back, arms depending from the back, two levers pivoted at one end to one of said arms and at the other to the frame and means for insuring simultaneous movement of said arms in reversing the back including pins on said arms and a check-block pivoted on said frame, said block

having slots on opposite sides of its pivot with which said pins coact and surfaces arranged to steady the movement of said arms when either pin is out of its slot, substantially as set forth.

2. In a reversible seat, the combination with a frame, a seat and a back, of an arm depending from the back, two levers pivoted at their inner ends to said frame and at their outer ends to said arm, and means for insuring simultaneous movement of said levers in moving the seat from one operative position to the other comprising pins on said levers and a check-block pivoted on said frame intermediate the inner ends of said levers, said block having surfaces coacting with said levers and slots into and out of which said pins are adapted to move as the seat is reversed, substantially as set forth.

3. In a reversible seat, the combination with a frame, a seat and a back, of two parallel end plates forming part of said frame and supported thereby, said end plates being secured together, a back-supporting arm operating between said plates, reversing-levers pivoted at one end to said arm and at the other to one of said plates, pins on said levers and a check-block pivoted on one of said plates intermediate the inner ends of said levers, said block having surfaces coacting with said levers and slots into and out of which said pins are adapted to move as the seat is reversed, substantially as set forth.

4. In a reversible seat, the combination with a frame, a cushion and a back, of arms depending from said back, two levers pivoted at their inner ends to said frame in a vertical plane, and to one of said arms in the longitude thereof, and a check-block centrally pivoted to said frame and having semicircular cut-away portions and portions extending on either side of said cut-away portions, said portions coacting with studs carried by the inner ends of said levers, substantially as set forth.

5. In a reversible seat, the combination with a frame, a cushion and a back, of arms depending from said back, two levers pivoted at their inner ends to said frame in a vertical plane, and to one of said arms in the longitude thereof, and a check-block centrally pivoted to said frame and having on opposite sides of its pivotal point semicircular cut-away portions and portions extending on either side thereof, said portions coacting with studs carried by the inner ends of said levers, substantially as set forth.

6. In a reversible seat, the combination with a frame, a cushion and a back, of arms depending from said back, two levers pivoted at their inner ends to said frame in a vertical plane, and to one of said arms in the longitude thereof, and a check-block centrally pivoted to said frame and having on opposite sides of its pivotal point semicircular cut-

away portions, one of said portions coacting with a stud carried by one of said levers and the other cut-away portion coacting with a stud carried by the other of said levers, substantially as set forth.

7. In a reversible seat, the combination with a frame, a cushion and a back, of arms depending from said back, two levers pivoted at their inner ends to said frame in a vertical plane, and to one of said arms in the longitude thereof, and a check-block pivoted to said frame and having a semicircular cut-away portion and portions extending outwardly therefrom, said portions coacting with studs carried by one of said levers on opposite sides of its pivotal point, each of said studs coacting successively with said cut-away portion and then with a portion extending outwardly therefrom, substantially as set forth.

8. In a reversible seat, the combination with a frame, a cushion and a back, of arms depending from said back, two levers pivoted at their inner ends to said frame in a vertical plane, and to one of said arms in the longitude thereof, and a check-block pivoted to said frame and having on either side of its

pivotal point a semicircular cut-away portion and substantially straight portions extending outwardly therefrom, each of said levers being provided with studs on opposite sides of its pivotal point, coacting successively with said semicircular cut-away portions and with said substantially straight portions extending outwardly therefrom, substantially as set forth.

9. In a car-seat, the combination with a frame, a cushion and a back, of two parallel end plates forming part of said frame and supported thereby, said end plates being secured together, a back-supporting arm operating between said end plates, reversing-levers pivoted at one end to said arm and at the other end to one of said end plates, and a check-block intermediate of the inner ends of said levers and coacting with studs carried thereby, substantially as set forth.

This specification signed and witnessed this 16th day of May, 1905.

EDWARD G. BUDD.
